UNITED STATES PATENT OFFICE.

CHESTER D. HOFF, OF WINCHESTER, WASHINGTON.

APPLIANCE FOR CLEANING TUBES.

1,418,925.

Specification of Letters Patent. Patented June 6, 1922.

Application filed October 20, 1921. Serial No. 509,093.

To all whom it may concern:

Be it known that I, CHESTER D. HOFF, a citizen of the United States, residing at 5 Winchester, in the county of Grant and State of Washington, have invented a new and useful Appliance for Cleaning Tubes, of which the following is a specification.

This invention relates to a tire repair tool and has for its object the provision of a 10 device in which the implements necessary for the application of a patch to an inner tube are assembled in convenient and compact form.

Other objects will present themselves as 15 the description proceeds, it being within the province of the disclosure to improve generally and to enhance the utility of devices of that character to which the present invention appertains. It is to be understood 20 that, within the scope of what is claimed, slight changes may be made without departing from the spirit of the invention or sacrificing any of the advantages thereof.

In the drawing forming a part of this 25 specification:

Figure 1 is a longitudinal section through the device.

Figure 2 is a view in elevation of the upper portion of the tool.

Figure 3 is a view in side elevation of the 30 device.

Figure 4 is a view depicting the manner in which the device may be used and

Figure 5 is a view in end elevation.

35 Referring to the drawing by characters of reference, the body of the device comprises a tubular container 1 having an open end 2 provided with screw threads 3. The said container forms a handle for the tool and is 40 adapted to hold repair material, including patches, cement etc.

A second container 4, having a closed bottom 5, is screw threaded at 6 to match the threads 3, the said bottom forming a closure 45 for the container 1. The container 4 provides a reservoir for supplying gasoline used in cleaning a tube to be patched and has screw threaded to its upper open end a brush holder 7 which forms a closure for the reservoir.

50 The brush holder is provided with a central socket 8 in which an applying member, preferably in the form of a brush 9 is seated. A small hole 10 opens through the bottom of the socket to supply gasoline to the brush or mop. A cap 11 is screw threaded at 12

to the brush holder, which prevents evaporation of the cleansing fluid and protects the brush when not in use.

A scraping element 13 secured to the brush holder 7, adjacent its connection with the reservoir, serves to assist in cleaning the tube, being used in conjunction with the brush in a combined brushing and scraping operation. It will also be noted that the scraper 13 provides a stop or rest to prevent rolling 65 of the implement when placed on an inclined surface.

A buffing or roughening attachment 14 is also carried by the brush holder, the same having an active face 15 arranged at an 70 acute angle with respect to the handle. A downturned flange 16 stiffens the buffer and contacting with enlargements 17 and 18 on the members 4 and 11 respectively, serves to prevent said members from becoming loose, 75 or unscrewing.

In preparing an inner tube for the application of a patch the tool may be used as illustrated in Figure 4, the brush applying the cleansing fluid and being followed by the 80 buffer or roughener so that the cleaning and roughening operation may be carried on simultaneously, likewise, it will be noted, that when the tool is used as illustrated in Figure 4, a partial rotation of the same may be 85 made to bring the scraping element into action, it being unnecessary to remove the brush from the work or to materially change the angular relation of the handle to the work. 90

As shown in Figure 5 the buffer and scraper also form means for conveniently and securely gripping the brush holder when it is desired to apply the brush holder to the body or remove the same therefrom. As 95 illustrated the thumb is placed on the roughened portion of the buffer and the first finger on the flattened portion of the scraper. This forms a positive grip for the left hand on the relatively small brush holder, the 100 handle forming ample gripping surface for the right hand.

Having thus described the invention what is claimed is:

1. A device of the class described comprising an applying element, a scraping element located adjacent the applying element and adapted to cooperate with said element in a cleaning operation. 105

2. A fountain brush comprising a handle; 110

a brush holder; a closure for the brush holder; and a buffing element carried by the brush holder and cooperating with the handle and the closure to retain said members in closed position.

3. A device of the class described comprising a body; a brush holder; and a scraping element located on the brush holder and projecting beyond the periphery of the body,

the scraping element coacting with the end 10 of the body to form a support for the body.

In testimony that I claim the foregoing as my own, I have hereto affixed my signature in the presence of two witnesses.

CHESTER D. HOFF.

Witnesses:

T. H. TWINING,
W. J. ISAAK.
